UNITED STATES PATENT OFFICE.

LARS ANDERSON AND EDWIN F. ENGEL, OF CHICAGO, ILLINOIS, ASSIGNEES OF ONE-HALF TO GEORGE W. STAHL, OF CHICAGO, ILLINOIS.

CALORIC ENGINE.

1,073,065.

Specification of Letters Patent.

Patented Sept. 9, 1913.

Application filed July 3, 1911. Serial No. 636,712.

To all whom it may concern:

Be it known that we, LARS ANDERSON and EDWIN F. ENGEL, citizens of the United States, residing at Chicago, in the county 5 of Cook and State of Illinois, have invented certain new and useful Improvements in Caloric Engines, of which the following is a specification.

This invention relates to engines of a class 10 commonly known as hot-air engines which are impelled by the expansion of a fluid contained in a closed cylinder and the principal object of the invention is to provide an improved construction, combination and 15 arrangement of the several parts which shall result in a simple and cheap engine of the class described which is effective and efficient in operation.

Another object is to provide improved 20 means for replenishing the fluid within the cylinder.

A further object is to provide improved heating and cooling means for the fluid within the cylinder.

25 A still further object is to provide an improved construction and arrangement of parts whereby a dead-center is prevented.

For the attainment of these ends and the accomplishment of other new and useful 30 objects, as will appear, our invention consists in the features of novelty in the construction, combination and arrangement of the several parts hereinafter described and shown in the accompanying drawings, but 35 more particularly pointed out in the appended claims.

In the accompanying drawings, Figure 1 is a side elevation partly in section showing 40 an engine constructed in accordance with the principles of our invention. Fig. 2 is a longitudinal cross section of the same. Fig. 3 is a detail cross sectional view on the line 3—3, Fig. 1. Fig. 4 is a detail view of the fluid replenishing device. Fig. 5 is a detail 45 view of the plunger showing the communicating means between the plunger shell adjacent the reduced portion thereof, when the plunger is made in sections. Fig. 6 is a diagrammatic representation showing the 50 several movable parts in a position different than in Fig. 1; Fig. 7 is a diagrammatic representation showing the several parts

when the crank pin 33 is in the uppermost position; and Fig. 8 is a diagrammatic representation showing the several movable 55 parts in another position.

The operation of engines of this class has heretofore been attended with many difficulties, chief among which are the expansion and contraction of the fluid contained within 60 the cylinder, the replenishing of the cylinder with fluid and at a certain pressure, and the provision of suitable efficient connecting means between the reciprocating elements and the power shaft. This invention 65 is designed to overcome these difficulties and to present a construction in which the maximum efficiency may be attained.

Referring now more particularly to the drawings, the cylinder 10 is adapted to receive a plunger comprising a close-fitting portion 11 and a portion of reduced diameter 12. These plunger portions 11 and 12 are joined by a threaded portion 13 or are made integral, and adjacent the junction of the two portions a number of perforations 14 are provided in the shell which are adapted to form communication between the inside of the close-fitting portion 11 and the outside of the plunger shell. The 80 reduced portion 12 is closed at both ends to form a sealed chamber 15. This sealed chamber may be filled with fluid or fluid may be entirely withdrawn therefrom, a cap 16 being preferably provided at one end of 85 the reduced portion 12 to afford communication with the interior of the said reduced portion.

Attached to the cylinder is a cylinder cap 17 which is formed of any suitable heat-conducting material and is preferably of thinner construction than the cylinder 10 to facilitate the passage of heat through the cap. The plunger is adapted to move in the cylinder 10, the reduced portion 12 being moved within the cap 17 at the end 90 of a stroke. Since the portion 12 is reduced in diameter or cross section a space will be provided between the cylinder 10 or the cylinder cap 17 and the reduced portion 12. 95

Within the close-fitting portion 11 of the plunger a piston 18 is movable. Both the piston 18 and the close-fitting portion 11 are adapted to make air-tight connection. The 100

piston 18 is movable within the shell portion 11 and the latter is movable within the cylinder 10. It appears therefore that the movement of the piston is greater than the movement of the plunger shell 11, and, in the present exemplification of our invention the movement of the piston is substantially twice as great as the movement of the plunger. At the other end of the cylinder 10 a crank case 19 is secured and between the flanged connecting edges of the cylinder and the crank case are a plurality of openings 20. Surrounding the cylinder 10 is a casing 21 and the openings 20 are adapted to afford communication between the interior of the crank case 19 and the space formed by the casing 21. At the upper end of the casing there are provided a number of openings 22. These openings 20 and 22 are adapted to provide means for permitting a fluid to be drawn in from without the crank case and to be expelled therefrom through the chamber surrounding the cylinder 10 by the movement of the piston and plunger 11 in the cylinder whereby the cylinder will be cooled. It is contemplated that the fluid employed for cooling shall be air but it is also obvious that other cooling fluids may be employed to cool the cylinder.

The fluid contained within the cylinder upon the expansive force of which the operation of the engine depends may be any desired or suitable fluid, and in the present invention it is contemplated that air will be used as this fluid. The pumping action of the plunger and the piston in the cylinder is operative to expel some of the air from the closed portion of the cylinder by way of the crank case unless the connections between the plunger and the cylinder are absolutely air tight. In order that the air or fluid within the cylinder may be replenished there is provided an automatic device shown more clearly in Fig. 4, which is adapted to maintain the fluid within the cylinder at any desired pressure. It is found in practice that the pressure of the fluid within the cylinder should not differ greatly from the pressure of the atmosphere for the action of the plunger and piston in the cylinder at one end of the stroke is to compress the fluid and at the other end to rarefy it because of the great difference in displacement at the opposite ends of the stroke. It is evident therefore that a pressure intermediate of the maximum and minimum pressures is the most suitable. The fluid replenishing device comprises a vertical tube 23 threaded at one end to receive a cap 24 with an adjusting screw 25 and at the other end provided with an opening 26 in which a wedge-shaped plug 27 is adapted to fit. This plug 27 is free to move up and down in the tube, its upward motion being limited by the position of the adjusting screw 25. A connecting tube

28 affords communication between the interiors of the tube 23 and the cylinder 10. The action of this device depends upon the pressure of the air within the cylinder. When the piston and plunger move to rarefy the fluid within the cylinder the tendency is to raise the plug 27 in the tube 23. If this suction pressure is of sufficient strength the plug 27 will be raised and enough air will be admitted through the opening 26 to replenish the air within the cylinder. This device may be adjusted by varying the size of the plug and by adjusting the position of the screw 25 so that any desired pressure may be maintained within the cylinder.

Attached to the plunger 11 are rods 29 and attached to the piston 18 is a piston rod 30. The engine shafts 31 are provided with crank disks 32 within the crank case and a crank pin 33 connects the crank disks. The rods 29 are pivotally connected to the crank pin 33 and the length of stroke of these bars 29 and the plunger may be adjusted by adjusting the position of the crank pin with respect to the crank disks 32. Pivotally mounted upon this crank pin 33 and preferably intermediate of the pivotal connection of the bars 29 therewith is a lever having lever arms 34 and 35. This lever has pivotal connection at one end to the piston rod 30 and at the other end to a link or bar 36. The link 36 is pivotally connected at its other end to some fixed point in the crank case as 37. The piston rod 30 is formed with its ends at an angle to each other, as are also the arms 34 and 35 of the lever connected to the piston rod. By this means it is seen that the thrust of the piston rod upon the crank pin is at an angle to the thrust of the bars 29 connected to the plunger shell. From this it is evident that there will be no dead-center position and that the thrust imparted to the piston rod and the bars will be directly transmitted to the engine shaft through the crank pin and crank disks. It is furthermore evident that the movement of the piston is simultaneous with the movement of the plunger and that the length of stroke is greater, which necessitates that the speed of the piston must be greater than the speed of the plunger. The engine shafts are of course provided with fly-wheels 38 to equalize the power of the engine.

In operation the plunger and the piston compress the fluid in the cylinder at one end of the stroke, and by reference to Fig. 1 it will be evident that when the piston and plunger are at the compression end of the stroke the piston will be adjacent the apertures or openings in the plunger shell and the fluid will be compressed substantially within the space formed between the reduced portion 12 and the cylinder cap 17. Heat being applied to the cylinder cap 17 expands the fluid causing it to act upon the

plunger and upon the piston which thereupon are moved in a direction to permit of the further expansion of the fluid. The piston moving downwardly draws the fluid 5 from the outside of the plunger shell through the apertures 14 within the close-fitting portion 11 which is surrounded by the cylinder 10. The cylinder being cooled on the outside cools the fluid within the close-fitting 10 portion, and in addition the rapid movement of the piston within the plunger shell 11 has a rarefying effect which further acts to cool the fluid. It will be noticed that the heating and cooling system is of the maximum 15 efficiency for the reason that heat is applied in the cylinder cap to a thin body of fluid and that the action of the engine itself is utilized in the cooling of the fluid within the cylinder as well as the rarefying 20 of the fluid by means of the piston action. By sealing the chamber 15 and exhausting the air therefrom the heating action in the cap 17 is further assisted and the heating efficiency of the engine is thereby increased. 25 While we have thus described the preferred construction, combination and arrangement of the several parts which constitute our invention, it is evident that those skilled in the arts to which this appertains 30 may make various changes in the construction, combination and arrangement of such parts without departing from the spirit and scope of our invention.

Claims.

- 35 1. In an engine of the class described, the combination of a cylinder, a plunger movable therein, and means movable simultaneously therewith to vary the expansive space in the cylinder.
- 40 2. In an engine of the class described, the combination of a cylinder, a plunger movable therein, and a piston movable simultaneously with the plunger and at a different speed.
- 45 3. In an engine of the class described, the combination of a cylinder, a plunger movable therein, and a piston movable in the said plunger at the same time and at a different speed.
- 50 4. In an engine of the class described, the combination of a cylinder, a plunger movable therein, and a piston movable in the plunger at the same time in the same direction and at a different speed.
- 55 5. In an engine of the class described, the combination of a cylinder, a plunger movable therein, a piston movable within the said plunger at the bottom thereof, and means to vary the pressure within the cylinder more rapidly than the movement of the plunger varies.
- 60 6. In an engine of the class described, the combination of a cylinder, a plunger the lower part of which fits closely within the cylinder, a piston slideable within the close-

fitting portion of the said plunger, and means to move the piston in accordance with the movement of the plunger and at a different speed to vary the pressure of fluid within the cylinder.

70 7. In an engine of the class described, the combination of a cylinder, a plunger within a closed portion of the cylinder and movable within the cylinder, a piston movable in the plunger at a speed different from that of the plunger, the piston and plunger comprising a closed chamber in the cylinder which is varied in size in accordance with the movement of the piston.

75 8. In an engine of the class described, the combination of a cylinder, a plunger movable in the cylinder, a portion of the plunger fitting closely and another portion provided with a closed chamber fitting loosely on the said cylinder, and a piston movable in the close-fitting portion of the plunger at a speed different than that of the shell, the said plunger being provided with means forming communication between the interior of the close fitting portion and the cylinder 80 surrounding the loose-fitting portion.

85 9. In an engine of the class described, the combination of a cylinder, a plunger shell movable within the cylinder, a portion of the shell fitting closely within the cylinder 90 and an extension thereof of smaller diameter forming a closed chamber, perforations being disposed in the shell between the close fitting portion and the other portion to provide communication between the interior of the close fitting portion of the shell and the cylindrical space about the portion of smaller diameter, and a piston movable in the close fitting portion of the shell operative to move fluid through the perforations 95 as the piston moves.

100 10. In an engine of the class described, the combination of a cylinder, a plunger movable within the cylinder, the plunger being formed with a close-fitting portion and a portion of reduced diameter, the latter being closed to form a sealed chamber, and with perforations in the shell between the two portions, and a piston movable within the close-fitting portion of the plunger and operative in conjunction with the said plunger to vary the displacement in accordance with the movement of the piston and the plunger.

110 11. In a caloric engine, the combination of a cylinder, a cylinder cap secured to the cylinder, a plunger movable within the cylinder and formed with a portion which fits the cylinder closely and another portion which is reduced in diameter and extends within the said cap when the plunger is at one end 115 of its stroke, the said reduced portion forming a closed sealed chamber, and the plunger being provided with perforations through the shell between the two said portions, and a piston movable within the close fitting 120 portion.

- portion of the plunger at a different speed than the said plunger and operative to force the air in and out of the perforations in accordance with the movements of the plunger and the piston.
12. In a caloric engine, the combination of a cylinder, a cylinder cap of heat conducting material secured thereto, a plunger movable within the cylinder having a portion which fits the cylinder closely and another portion reduced in size and forming an air-tight chamber which extends within the said cap and with perforations through the plunger where the two said portions thereof meet, a piston movable within the close-fitting portion of the plunger at a different speed than that of the plunger, the said cylinder having the greatest displacement when the plunger and piston are at one end of the stroke and the smallest displacement when they are at the other end of the stroke.
13. In a caloric engine, the combination of a cylinder, a cylinder cap of heat-conducting material secured thereto, a plunger movable within the cylinder having a portion which fits the cylinder closely and another portion reduced in diameter and forming a sealed chamber which is positioned to extend within the said cap at one end of the stroke and with perforations through the plunger where the two said portions thereof meet, a piston movable within the close fitting portion of the plunger at a different speed than the plunger, the said piston and plunger forming with the cylinder a closed variable chamber, the fluid in the cylinder being under compression at one end of the stroke and rarefied at the other end thereof.
14. In an engine of the class described, the combination of a cylinder, a plunger having a close fitting shell portion movable in the cylinder, a piston movable within the close fitting portion, the piston and plunger forming with the cylinder a closed chamber for containing expansible fluid, and means to replenish the fluid in the closed cylinder chamber.
15. In an engine of the class described, the combination of a cylinder, a plunger having a close fitting shell portion movable in the cylinder, a piston movable within the close fitting portion, the piston and plunger forming with the cylinder a closed chamber for containing expansible fluid, and an automatic device operative to permit the inflowing of fluid to the cylinder chamber and to prevent the outflow thereof.
16. In an engine of the class described, the combination of a cylinder, a plunger having a close fitting shell portion movable in the cylinder, a piston movable within the close fitting portion, the piston and plunger forming with the cylinder a closed chamber for containing expansible fluid, and a

device automatically operable to maintain the fluid in the cylinder chamber at a given density.

17. In an engine of the class described, the combination of a cylinder, a plunger having a close fitting shell portion movable in the cylinder, a piston movable within the close fitting portion, the piston and plunger forming with the cylinder a closed chamber for containing expansible fluid, and a device automatically operable to maintain the fluid in the cylinder chamber at a given density and comprising a vertical tube having communication with the cylinder chamber threaded at the upper end and with a tapered opening in the bottom, a tapered plug movable in the tube and adapted to close the bottom opening, a threaded plug for the top of the tube, and an adjusting pin to regulate the height to which the movable plug may rise.

18. In a caloric engine, the combination of a cylinder, a plunger having a close fitting shell portion and a portion of reduced diameter forming a sealed chamber, a cylinder cap of heat conducting material, the sealed chamber portion extending within the said cap at the end of a stroke, a piston movable within the close fitting portion of the plunger, a piston rod, a closed crank case, a casing surrounding the said cylinder and provided with communicating openings to the crank case and in the portion of the casing remote from the crank case openings, the movement of the piston in the cylinder being operating to draw air into and to expel it from the crank case through the said cylinder casing to cool the cylinder, the cylinder cap being adapted to be heated to expand the fluid therein contained.

19. In an engine of the class described, the combination of a cylinder, a plunger having a close fitting shell portion movable in the cylinder, a piston movable in the said shell portion, a crank case, and means whereby the piston is moved at a different speed and in the same direction as the plunger, the latter being impelled by the same expansive force as that applied to the plunger.

20. In a fluid expansive engine of the class described, the combination with a cylinder, of a plunger having a close fitting shell portion movable therein, a piston movable within the said shell portion, a piston rod attached to the plunger, a separate piston rod attached to the said piston, an engine crank, the said rods being both attached to the said crank, and means in connection with a fixed point and one of said piston rods to cause it to move at a different speed than the other, both the plunger and the piston being impelled in the same direction by the same expansive force.

21. In a fluid expansive engine of the

class described, the combination with a cylinder, of a plunger having a close fitting shell portion movable therein, a piston movable within the said shell portion, a piston rod attached to the said piston, a crank case, an engine shaft and crank rotatable in the crank case, the said rods being attached to the engine crank, and means whereby the piston is moved in the same direction at a faster rate of speed than the said plunger.

22. In an engine of the class described, the combination with a cylinder, of a plunger shell having a close fitting portion and a portion reduced in diameter and forming a closed chamber, a cylinder cap secured to the cylinder into which the plunger extends at one end of the stroke, a piston movable in the said shell portion, means whereby the piston is moved in the same direction simultaneously with the plunger with a stroke of greater length, the piston and the plunger being impelled by the same expansive force.

23. In an engine of the class described, the combination with a cylinder, of a plunger with a shell portion and movable in the cylinder, a piston movable in the shell portion of the plunger, a crank case, an engine shaft and crank, and means in connection with the crank and the piston and plunger whereby the piston is moved at a greater rate of speed than the plunger, the length of stroke of the piston being greater than that of the plunger.

35 24. In an engine of the class described, the combination with a cylinder, of a plunger with a shell portion and movable in the cylinder, a piston movable in the shell portion of the plunger, a crank case, an engine shaft and crank, a crank pin secured to the crank, a rod to connect the plunger to the crank pin, a piston rod secured to the piston, a lever pivoted on the crank pin having one arm pivotally connected with the piston rod, and means to connect the other lever arm to a fixed point, the said lever in connection with the piston rod being operative to permit a greater speed of motion of the piston than of the plunger.

50 25. In an engine of the class described, the combination with a cylinder, of a plunger with a shell portion and movable in the cylinder, a piston movable in the shell portion of the plunger, a crank case, an engine shaft and crank, a crank pin secured to the crank, a rod to connect the plunger to the crank pin, a piston rod secured to the piston, a lever pivoted on the crank pin having one arm pivotally connected with the piston rod, a

bar pivotally connected at one end to a fixed point and at the other end to the other arm of the said lever, the piston rod being connected to and bearing upon the crank pin at a different angle than that of the rod connected to the plunger.

65

26. In an engine of the class described, the combination with a cylinder, of a plunger with a shell portion and movable in the cylinder, a piston movable in the shell portion of the plunger, a crank case, an engine shaft and crank, a crank pin secured to the crank, a rod to connect the plunger to the crank pin, a piston rod secured to the piston, a lever pivoted on the crank pin having one arm pivotally connected with the piston rod, means to connect the other lever arm to a fixed point, and means to adjust the length of stroke of the piston and plunger.

70

27. In an engine of the class described, the combination with a cylinder, of a plunger with a shell portion and movable in the cylinder, a piston movable in the shell portion of the plunger, a crank case, an engine shaft and crank, a crank pin secured to the crank, a rod to connect the plunger to the crank pin, a piston rod secured to the piston, a lever pivoted on the crank pin having one arm pivotally connected with the piston rod, means adjustably to connect the other lever arm to a fixed point, and means to adjust the length of stroke of the piston independently of the length of stroke of the plunger.

80

28. In an engine of the class described, the combination with a cylinder, of a plunger with a shell portion and movable in the cylinder, a piston movable in the shell portion of the plunger, a crank case, an engine shaft and crank, a crank pin secured to the crank, means to connect the plunger to the crank pin, a piston rod with end portions bent out of alignment, a lever pivotally connected with the crank pin and having connection with the end of the piston rod, and means to connect the other end of the said lever to a given point, the piston rod being operated at an angle to the plunger connecting means whereby a dead-center is prevented.
